No. 36,602.

Patented October 27, 1903.

UNITED STATES PATENT OFFICE.

OTIS M. FREEMAN, OF PROVIDENCE, RHODE ISLAND.

DESIGN FOR A WATCHCASE.

SPECIFICATION forming part of Design No. 36,602, dated October 27, 1903.

Application filed January 19, 1903. Serial No. 139,708. Term of patent 14 years.

To all whom it may concern:

Be it known that I, OTIS M. FREEMAN, a resident of Providence, in the county of Providence and State of Rhode Island, have invented a certain new, original, and ornamental Design for Watchcases.

My invention consists of an ornamental design of that portion of a watchcase which incloses or embraces the winding-stem, of which—

Figure 1 is a plan view. Fig. 2 is a side elevation of a watchcase, showing an ornamental setting for the winding-stem, which is mounted on said case.

What I claim as new, and desire to secure 15 by Letters Patent, is—

The ornamental design for a watchcase as herein shown.

In testimony whereof I have signed my name to this specification in the presence of 20 two subscribing witnesses.

OTIS M. FREEMAN.
